CLAIM

The ornamental design for a tumbler, as shown and described.

DESCRIPTION

FIG. 1 is a top, perspective view of my new design for a tumbler.

FIG. 2 is a left side elevation view of the tumbler of FIG. 1. FIG. 3 is a right side elevation view of the tumbler of FIG. 1.

FIG. 4 is a rear view of the tumbler of FIG. 1.

FIG. 5 is a front view of the tumbler of FIG. 1.

FIG. 6 is a top view of the tumbler of FIG. 1; and,

FIG. 7 is a bottom view of the tumbler of FIG. 1.

Broken lines shown are for illustrative purposes and form no part of the claimed design.

1 Claim, 6 Drawing Sheets
